UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CONDUCTOR SUPPORT.

Application filed October 1, 1923. Serial No. 665,773.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Con-
ductor Supports, of which the following is
a specification.

My invention relates to conductor sup-
10 ports and has particular reference to that
class of support used in connection with
trolley conductors which cross each other,
and which is designed to arrange for the
current collector to pass the crossing point
15 without being thrown out of electrical
engagement with its conductor.

The object of my invention is to produce
a device which is simple, efficient, light in
construction and easy to install, and my in-
20 vention resides in the new and novel con-
struction, combination and relation of the
various parts as herein disclosed and fur-
ther set forth in the drawing accompanying
this specification.

25 In the drawing:

Figure 1 is a side view in elevation of
the center support and two diametrically
disposed arms, all of which are shown in
relation with the crossed trolley conductors.

30 Fig. 2 is a sectional view of the center
structure of my invention taken on the line
2-2 of Fig. 1.

Fig. 3 is a sectional view on the line 3-3
of Fig. 1.

35 Fig. 4 is a bottom plan view of my inven-
tion shown as secured to two trolley wires
crossing each other at right angles.

Fig. 5 is a top plan view of the center
structure of my invention shown as secured
40 to two crossed trolley wires at right angles
to each other.

Fig. 6 is a sectional view of the end por-
tion of one of the radiating arms taken, as
for instance, on the line 6-6 of Fig. 4.

45 Fig. 7 is a sectional view on the line 7-7
of Fig. 2.

In the preferred construction embodying
my invention I employ a lower member 1
and an upper member 2. The lower member
50 is provided with a plurality of projecting
studs 3 which are usually arranged in pairs
diametrically opposite each other. The pro-
jecting studs are not continuous at the cen-
ter, but are spaced apart, leaving a space or
55 gap 4. Interposed in the center of the

space or gap 4 is a projecting stud 5 which
tends to shorten the gap between the diamet-
rically disposed studs 3 in order to assist
in guiding the current collector from one
stud across to the opposite stud. The mem-
ber 1 is also provided with a socketed recess
60 and shown as internally threaded in Fig. 2.
The projecting studs 3 are provided with
other projecting studs 4' to which are se-
cured tubular projecting arms 5' by means
65 of rivets or pins 6. The upper member 2
is composed of two clamping members 7 and
8. Each member is provided with channels
9 and 10 respectively and angularly disposed
70 to each other to receive the trolley wires 11 and 12. The clamping members 7 and 8 are
held in fixed relation to each other and to
the trolley wires 11 and 12 by means of
bolts or cap screws 13 as shown. When the
members 7 and 8 are in position the trolley
75 wires are in contact with each other and dis-
posed in their corresponding groove in the
member 7 or 8 and are fixedly held there by
the fastening members 13. The angularity
of the grooves or channels 9 and 10 depends
80 upon the angle at which the trolley wires
cross each other. The same is true of the an-
gular spacing of the members 3 of the lower
member 1.

The member 7 is provided with a project-
ing member 14 which in turn is provided
85 with a socketed recess 15. Positioned in the
recess 15 is the head of a bolt 16, the shank
of which projects downwardly therefrom
and is secured in the threaded recess in the
lower member 1. The side walls of the re-
cess 15 correspond with the side faces of the
90 head of the bolt 16 as shown in Fig. 7 so that
the two may be rotated simultaneously. In-
terposed between the lower face of the head
of the bolt 16 and the adjacent face or wall
95 of the member 14 is a flat spring 17 which
tends to hold the lower and upper members
1 and 2 in engagement with each other when
in normal position.

To the outer ends of the members 5 is se-
cured an end member 18 provided with a
groove formed by means of the lips 19 to re-
ceive the trolley wires 11 and 12. The lips
19 originally form a U shaped groove which
100 is readily applied to the trolley wire and
when the lips are peened over as shown in
Fig. 3 the end members 18 are securely at-
tached to the trolley wires. The end mem-
ber 18 is provided with a projecting stud 20
105

which is inserted within the tubular arm 5' and secured thereto by means of the pins or studs 21.

In assembling the various parts, the bolt 16 is first positioned in the member 7 with the spring 17 interposed as shown in Fig. 2. By rotating the member 7 the threaded portion of the bolt 16 can be made to engage with the member 1, and when the members 1 and 7 have been brought together by rotating to the limit of rotation, the members are backed off a sufficient amount to bring the groove 9 in the member 7 in proper alignment with the nearest arm 5'. The spring 17 being under compression, will maintain the members 7 and 1 in engagement with each other and, therefore, prevent movement of these parts due to the backing off of the member 7 relative to the member 1. The tubular arms 5' are secured to the projections 4' and 20 as shown. Having assembled the parts thus far, these assembled parts are placed in position with respect to the trolley wires and the lips 19 peened into position and the member 8 then secured in position by means of the bolts 13, or these two latter operations may be reversed, the member 8 being secured in position prior to the lips 19 being peened into place.

There are many modifications in the details of construction of my invention which, it will be quite evident, can be made and still maintain the feature of my invention.

My invention gives a simple, light and efficient device and one in which long approach arms 5' may be used without excessive cost or weight.

Having described my invention, I claim:

1. An article of manufacture comprising a member provided with a plurality of radiating arms, means on the end of each arm to engage and grip a conductor, a second member mounted above the first member and secured thereto and having means to engage and grip the trolley conductors and means on the first member to permit a current collector to pass from one arm to a diametrically disposed arm.

2. An article of manufacture comprising a member provided with a plurality of radiating arms, means on the end of each arm to engage and grip a conductor, a second member mounted on the first member and secured thereto in rotatable relation, means secured to the second member to grip a plurality of crossed conductors therebetween.

3. An article of manufacture comprising a member provided with a plurality of radiating arms, means on the end of each arm to engage and grip a conductor, a second member rotatably secured to the first member and provided with means to grip a plurality of conductors.

4. An article of manufacture comprising a member provided with radial projections, a

tubular arm secured to each projection, gripping means secured to the end of each arm and provided with means to grip a conductor, a second member secured to the first member and provided with means to grip a plurality of crossed conductors.

5. A center construction for a cross-over device comprising a member having a plurality of radiating projections to receive arms, a rotatable member secured to the first member and provided with a socket, a fastening device in said socket and engaging the first member and a clamping member secured to the rotatable member to engage and grip a plurality of conductors.

6. A center construction for a cross-over device comprising a member having a plurality of radiating projections to receive arms, a second member detachably secured to the first member and comprising two parts between which are positioned a plurality of crossed conductors and means to draw the two said parts into gripping engagement with the conductors.

7. A center construction for a cross-over device comprising a member provided with means to receive a plurality of radiating arms, a second member secured to the first member and comprising two parts to receive and grip a plurality of crossed conductors therebetween and means to move the parts into gripping engagement with the conductors.

8. A center construction for a cross-over device comprising a member provided with means to receive a plurality of radiating arms, a second member secured to the first member in detachable and rotatable relation thereto and means on the second member to receive and grip a plurality of crossed conductors.

9. A center construction for a cross-over device comprising a member provided with means to receive a plurality of radiating arms, a second member secured to the first member in detachable relation thereto, means to yieldingly maintain the members in engagement and means on the second member to receive and grip a plurality of crossed conductors.

10. A center construction for a cross-over device comprising a member provided with means to receive a plurality of radiating arms, a second member secured to the first member in rotatable relation thereto, means to yieldingly maintain the members in engagement and means on the second member to receive and grip a plurality of crossed conductors.

11. An end member for the radiating arms of a cross-over device comprising a body having a U shaped groove therein formed by bendable lips to receive and grip a conductor and means projecting from said body to receive an arm of the cross-over

device and means forming a runway for a current collector from the conductor to the arm or vice versa.

12. An end member for the radiating arms of a cross-over device comprising a body having a U shaped groove therein formed by bendable lips to receive and grip a conductor and means projecting from said body to receive a tubular arm of the cross-over device and means forming a runway for a current collector from the conductor to the arm or vice versa.

13. A center construction with a cross-over device comprising a member provided with means to receive a plurality of radiating arms and means to receive a plurality of crossed conductors and means cooperating with said means to engage and grip the conductors therebetween.

In testimony whereof I affix my signature.

SAMUEL S. MATTHES.
